US00D524468S

(12) **United States Design Patent** (10) **Patent No.:** **US D524,468 S**
Chean (45) **Date of Patent:** **** Jul. 4, 2006**

(54) **PORTABLE LIGHT EMITTING DIODE FLASHLIGHT**

D497,445 S * 10/2004 Chan D26/37
D501,055 S * 1/2005 Packard D26/37
D504,529 S * 4/2005 Vickers et al. D26/37

(75) Inventor: **Leo Wong Sung Chean**, Singapore (SG)

* cited by examiner

(73) Assignee: **Light 10 Pte. Ltd. (SG)**

Primary Examiner—Marcus A. Jackson

(**) Term: **14 Years**

(74) *Attorney, Agent, or Firm*—Arent Fox PLLC

(21) Appl. No.: **29/228,354**

(57) **CLAIM**

(22) Filed: **Apr. 22, 2005**

The ornamental design for a portable light emitting diode flashlight, as shown.

(30) **Foreign Application Priority Data**

DESCRIPTION

Oct. 26, 2004 (SG) D2004/1851/D

FIG. 1 is a perspective view of the embodiment of my invention;

(51) **LOC (8) Cl.** **26-02**

FIG. 2 is a front view thereof;

(52) **U.S. Cl.** **D26/37**

FIG. 3 is a right view thereof;

(58) **Field of Classification Search** D26/37-50;

FIG. 4 is a left view thereof;

362/157, 158, 171-174, 183-208

FIG. 5a is a top view thereof; and,

See application file for complete search history.

FIG. 5b is a bottom view thereof.
